UNITED STATES PATENT OFFICE.

JAMES M. HAWES, OF GREAT FALLS, NEW HAMPSHIRE.

DEVICE FOR TURNING SHAFTING.

SPECIFICATION forming part of Letters Patent No. 261,344, dated July 18, 1882.

Application filed November 9, 1881. (No model.)

To all whom it may concern:

Be it known that I, JAMES M. HAWES, of Great Falls, in the county of Strafford and State of New Hampshire, have invented an Improved Dressing-Head for Finishing and Smoothing Shafting; and I do hereby declare that the following is a full and exact description thereof, reference being had to the accompanying drawings, making part of this specification—

Figure 1 being a front view of the dressing-head; Fig. 2, a view of the same, the inclosing cap or plate being removed; Fig. 3, a section, as in the plane indicated by the line $\alpha\alpha$, Fig. 1, showing the parts constructed for admitting the smoothing-cutter in place of one of the bearing-slides; Fig. 4, a view of parts thereof detached.

Like letters designate corresponding parts in all of the figures.

In the construction of this instrument I employ a stationary ring-disk, A, through the open center of which the shaft or tube to be finished round and smoothed is to pass, the said disk being secured to a suitable holding yoke or frame and the shaft to be revolved therein and fed along through it. This disk for finishing shafts varying in size—say from three-fourths of an inch to four inches in diameter—
50 may be about ten inches in diameter, the central aperture thereof being of sufficient size to admit the largest shafting to be finished by the instrument. One side of the disk has two inwardly-projecting flanges, $a b$, one at the outer and the other at the inner periphery thereof, as shown in Fig. 2, both projecting sufficiently from the face of the disk to admit the operative parts of the instrument (hereinafter set forth) therein. The flange side of the disk is
55 or may be covered with another ring-disk or face-plate, B, thus inclosing the parts located between the flanges. This plate or disk is secured to the flanged disk by screws $c c$, so that it may be readily removed. In the flanges $a b$ mortises or guideways are formed for the reception of radial bearing-slides C C, arranged at suitable and preferably uniform intervals around the circle, as shown, the inner ends of which, when adjusted to an exact circle of the required diameter, serve unitedly as a bearing to hold and center the shaft to be smoothed. In order to adjust these slides out and in to

suit different diameters of shafts, I form lateral heads or projections $d d$ on their outer ends, through which radial screws E E pass 55 and thence screw into the outer flange, a , of the disk A, substantially as represented. The heads $f f$ of these set-screws bear against the outer surfaces of the slide-heads $d d$, and jam-nuts $g g$ on the screws are tightened against 60 the inner surfaces of these heads $d d$ when the slides are properly adjusted for any diameter of shaft. Also, in a suitable way or ways of the disk A a smoothing-cutter, G, is located, so as to be similarly adjusted in a radial position and direction out and in to suit the size of shaft to be finished. This cutter is or may be adjusted by a set-screw, H, in the same manner as the bearing-slides, between two of which it is located. It is to be understood 70 that this smoothing-cutter is situated an inch or two behind a suitable instrument for first reducing the shaft to a uniform size, and that its action on the shaft follows the reducing action and by the same movement of the shaft, 75 though this is not essential. For perfect work this smoothing-cutter is also to precede the position of the bearing-slides C C, which therefore hold the shaft always where it is finished, so that their holding thereof is always as accurate as possible. Hence I make the guideway of the cutter just forward of those of the bearing-slides in the holding-disks, as shown or indicated in Figs. 1 and 2. In many cases, however, I find it desirable and generally preferable to adapt the cutter to be inserted in one of the slideways and constructed to be adjusted in the same way. The slide C, which is removed to permit the insertion of the cutter, is not essential to a proper centering of the shaft, 80 there being enough left for that purpose. This construction is especially shown in Fig. 3. To enable this to be effected the cutter and slides have at their inner ends the form and relation to each other indicated in Fig. 4, which exhibits the relative positions of the cutter and guides as they advance over the shaft in the direction shown by the arrow, or as, in fact, (and which amounts to the same thing,) the shaft moves in the opposite direction. The 85 back part or corner, i , of the cutter is cut or chamfered away, and the front part or corner, l , of each slide is cut or chamfered away, as indicated in the drawings, the chamferings of

the two meeting at the same point. Thus it will be seen that the working-surface *m* of the cutter precedes the working-surfaces *n* of the slides, the shaft-surface not being completely reduced by the cutter till the rear end of the cutting-edge thereof passes over it, and thereby the purpose is effected.

This instrument finishes shafting complete for use.

10. What I claim as my invention, and desire to secure by Letters Patent, is—

A dressing-head for finishing shafts, composed of the ring-disk *A*, provided with two

concentric guide-flanges, *ab*, the bearing-slides *C C*, and cutter *G*, guided in the two flanges, 15 and the adjusting-screws *E E II*, screwing into the outer flange, *a*, for adjusting the said slides and cutter, substantially as and for the purpose herein specified.

The foregoing specification signed by me 20 this 24th day of June, 1881.

J. M. HAWES.
